RADIANT GAS HEATER

George D. Eddy, South San Gabriel, Calif.
Application October 5, 1955, Serial No. 38,233

Term of patent 14 years
(Cl. D81—10)

FIG. 4.

Fig. 1 is a perspective view of a radiant gas heater showing my new design;

Fig. 2 is a top plan view thereof;

Fig. 3 is a front elevation view thereof; and

Fig. 4 is a side elevation view.

I claim:

The ornamental design for radiant gas heater, as shown.
